UNITED STATES PATENT OFFICE.

WILLIAM H. KELLER, OF PHILADELPHIA, PENNSYLVANIA.

PNEUMATIC TOOL.

No. 856,706.

Specification of Letters Patent.

Patented June 11, 1907.

Application filed January 9, 1906. Serial No. 295,230.

To all whom it may concern:

Be it known that I, WILLIAM H. KELLER, a citizen of the United States, residing in the city and county of Philadelphia, State of Pennsylvania, have invented a new and useful Improvement in Pneumatic Tools, of which the following is a specification.

My invention relates to a novel construction of a pneumatic tool and a valve mechanism for a pneumatic tool wherein cost of production is reduced to a minimum and the construction greatly simplified. Many attempts have heretofore been made to produce a valve mechanism which will accomplish the desired results, but so far as I am aware it has hitherto been considered impossible and impracticable to employ the same valve mechanism for both a long stroke or short stroke hammer, irrespective of whether the piston be grooved or ungrooved.

In my present invention I have succeeded by my novel construction of valve, valve box and its adjuncts, in producing a tool wherein the necessity of fitting a cap on the valve box is avoided, since the said cap is dispensed with and I also employ a balanced valve of symmetrical construction having both ends constructed alike and wherein the valve can be inserted in the valve box, either end foremost, and wherein the same type of valve and valve box can be applied to a short stroke or to a long stroke tool and a solid piston or a grooved piston may be employed with equal facility.

So far as I am aware, I am the first in the art to produce a valve mechanism wherein it is possible to secure any desired length of stroke without materially changing the whole construction of the cylinder and ports. In many pneumatic tools as heretofore constructed wherein a fluid actuated valve is used to control the movement of the hammer or piston, the valve has been moved either in an opposite direction or a right angle to the movement of said hammer or piston in which case the blow of the hammer will naturally interfere with the regular and uniform movement of the valve, if the latter does not move in the same direction as the piston, and if the valve does not work regularly and uniformly the reciprocations of the piston will be irregular which is a very objectionable feature and very often renders the use of pneumatic hammers impracticable. This irregular movement of the hammering piston some-

times also causes the valve to break or become injured and thus shortens the life of the tool. Since it will be apparent that if the valve moves in the opposite direction to the piston shortly before the latter strikes the chisel, or if the valve should move in an opposite direction to the piston at the moment that the piston delivers its blow the valve will be liable to rebound from its seat, reopen ports that should be closed and cause the tool to jump; or in other words, the cylinder or easing will move away from the chisel or the working tool, because the exhaust from the back end does not occur at the right time.

Now, since hammers of the character of my novel construction under consideration strike from two to three thousand blows per minute, it will be readily seen how wearing this irregular movement will be both on the valve and the operator. By my novel invention, however, before the hammer strikes the chisel or working tool, the valve will move in the same direction and when the blow is delivered to the working tool the valve following the piston, the blow instead of rebounding the valve from the seat will serve to hold said valve more firmly seated, whereby all the ports are positively opened at the right time, the movement of the hammer is regular and unobstructed under all conditions and the jumping or fluttering of the valve which has heretofore been an objectionable feature in most pneumatic hammers is overcome.

A very objectionable feature in many pneumatic tools now on the market arises from the excessive shock and vibration caused by the rapid reciprocations of the piston and for the other reasons before specified which, in my present invention are reduced to a minimum whereby my invention can be applied not only to light work such as cutting or dressing stone and calking boilers or vessels, but for chipping and riveting on metal and for performing various kinds of work ordinarily heretofore performed by simple hand tools and a mallet or hammer.

To the above ends my invention consists broadly of a novel construction of valve, and valve box, said valve being capable of being inserted either end first, into the valve box and requiring no other cover or machine work of the character required when a valve box comprising two or more parts is used.

It further consists of a novel construction

of a tool cylinder, valve box and valve and co-acting ports and passages in said cylinder and valve box.

It further consists of other novel features 5 of construction, all as will be hereinafter set forth.

Figure 1 represents a longitudinal sectional view of a pneumatic tool and its adjuncts embodying my invention, the piston and 10 valve being shown in their rearward position. Fig. 2 represents a longitudinal section similar to Fig. 1 but showing the section taken on a different line and the piston and the valve in their extreme forward position. 15 Fig. 3 represents a section taken on the same line as Fig. 2 but showing the valve in its rearmost position and the piston just completing its forward movement. Fig. 4 represents a perspective view of my novel construction of valve employed in detached position. Fig. 5 represents a longitudinal sectional view of a long stroke pneumatic riveting hammer embodying my invention, the piston and valve being shown in their extreme forward position. 20 Fig. 6 represents a sectional view taken on a different line from Fig. 5 and showing the piston and valve in the rearward position they assume. Fig. 7 represents a sectional view of my invention 25 and embodied in a chipping hammer having a grooved piston, the piston and valve being shown in their extreme forward position. Fig. 8 represents another view similar to Fig. 7 but showing the valve and piston in a different position.

Similar numerals of reference indicate corresponding parts in the figures.

Referring to the drawings: In the detailed description of my novel construction, I shall 30 trace the course of the motive fluid from its entrance into the handle which may be of any suitable or conventional construction and shall describe the passage of the motive fluid from the time it enters the handle, 35 passes through and beyond the valve on either side thereof and during its inlet to either side of the piston and shall trace the exhaust of the motive fluid from both ends of the piston and valve.

Referring first to Figs. 1 to 4 inclusive, it 40 will be seen that when the parts are in the position seen in Fig. 1, the motive fluid enters the pressure supply duct 1 in the handle and flows thence into the passage 2 and 45 thence into the passage 3 of the valve box and through the groove 4 of the valve box around the forward groove 5 of the valve 6, assuming the latter to be in its rearmost position as seen in Figs. 1 and 3. The motive 50 fluid then passes through the ports 7 of the valve box and the passage 8 into the rear portion of the piston chamber 9 and assuming that the piston 10 is in the position seen in Fig. 1, said piston will be driven forwardly 55 from the position seen in Fig. 1 into the position seen in Fig. 2.

It will be observed that passages 11 and 12 of the valve box are always open to live air pressure and that when the valve is in the position seen in Fig. 1, live air can pass 60 freely through said passages 11 and 12 to the forward or left hand portion of the valve chamber 13, it being also apparent that live air pressure is always being exerted through the port 14 upon the rear end of the valve. 65 As the piston 10 moves toward the shank 15 of the working tool 16, the exhaust from the forward end of the piston flows through the port 17 and passage 18, best seen in Figs. 2 and 3, and passes thence through the passages 19 by the groove 20 of the valve 6 and thence through the port 21 into the annular chamber 22 and thence to the atmosphere through the exhaust ports 23, it being understood 70 that while the piston is exhausting from its forward end the valve 6 is in the position seen in Fig. 3 wherein the relative location of the ports 19 and 21 will clearly appear. After the piston 10 has moved into the position seen in Fig. 2 the port 24 is uncovered by the piston moving beyond it, whereby live air is permitted to flow through the port 25 passage 26 and port 24 into the piston chamber and thence through the port 27 and passages 28 and exhaust port 29 to 75 the annular exhaust chamber 22 and thence to the main exhaust ports 23. The pressure upon the forward end of the valve 6 is now relieved, whereupon the constant live pressure exerted through the live air port 14 will 80 force the valve 6 forwardly into the position seen in Fig. 2. The piston 10 and the valve 6 being now in their forward position, as seen in Fig. 2, the live air now flows through the passage 3, groove 4, around the neck 20 of the valve and thence through the passages 19 and 18 and port 17 to the forward end of the piston chamber 9, whereby the piston is 85 caused to move from the position seen in Fig. 2 rearwardly into the position seen in Fig. 1. While the piston is moving from the position seen in Fig. 2 to the position seen in Fig. 1, the exhaust from the rear or right hand end of the piston takes place at first 90 through the port 27, passages 28 and port 29, 95 annular chamber 22 and ports 23 to the atmosphere. After the piston 10 has moved rearward or toward the handle sufficiently 100 to cover the port 27, as seen in Fig. 3, the exhaust continues to take place through the passage 8, port 7, groove 5 of the valve and passage 29, annular chamber 22 and ports 23 to the atmosphere as seen in Fig. 2. The piston 10 has now moved rearwardly or 105 toward the handle into the position seen in Fig. 1 so that it uncovers the port 31, thereby permitting air in the rear or right hand portion of the valve chamber to escape 110

through the passages 32 and 33 and port 31 into the piston chamber 9 and thence through the port 30, passage 28, port 29, annular chamber 22 and exhaust ports 23 to the atmosphere, thereby causing the valve to move from the position seen in Fig. 2 into the position seen in Fig. 1 by reason of the live air pressure on the forward end of the valve which is permitted through passages 11 and 12.

It will of course be understood that while the piston is moving from the position seen in Fig. 1 to the position seen in Fig. 2, the initial exhaust flows through port 30, passage 28, port 29, annular chamber 22 and ports 23 to the atmosphere.

It will be further understood by reference to Fig. 4, that my novel construction of valve mechanism comprises essentially the valve 6 having a central head 34 and the outer heads or pressure areas 35 and 36 each of the outer heads being joined to the central head 34 by the necks 5 and 20 although it will be evident that this construction can be modified.

It will be seen from the foregoing that the valve of my novel construction of valve mechanism is symmetrical at both ends and has constant pressure on both ends and is shifted by intermittent exhaust at both ends.

By making the valve as described the same can be cheaply produced by automatic machinery and by reason of its being solid it is exceedingly durable under all conditions and since the valve is constructed the same at both ends, it can be inserted in the valve box either end foremost so that there is no possibility of the tool being improperly assembled in case the valve and valve box are disconnected for the purpose of inspection or repairs. I can employ the same type of valve mechanism for a long or short stroke or for any length of stroke which it is desired to impart to the piston and it will be further apparent that the stroke of the piston is not limited by the length of the piston.

By constructing the valve and valve box in the manner described, I am enabled to have a valve mechanism consisting of only two parts, the valve and the valve box and since the piston and valve simultaneously move in the same direction or in unison vibration is reduced to a minimum. By reason of the novel construction and collocation of the ports and passages intermediate the valve and piston, the tool will readily start in any position in which it may be held in the hands of the workman.

In the construction seen in Figs. 5 and 6, I have shown my novel valve mechanism as applied to a long stroke tool, that is a tool having a cylinder 37 of such length that the stroke of the piston is considerably in excess of its own length and since my same novel valve mechanism can be employed in this type of tool, as already described, I have

designated all the parts comprising the same, seen in Figs. 5 and 6, by the same reference letters as used for corresponding parts in the corresponding Figs. 2 and 1 respectively.

In Figs. 5 and 6 I have shown the piston employed as comprising a plain, ungrooved, solid, cylindrical shaft 38 of uniform diameter throughout its length both ends being of approximately the same contour and diameter. I have shown the type of tool illustrated in Figs. 5 and 6 as being equipped especially for riveting, the riveting die being indicated at 39 and having the shank 40 projecting into the end of the tool cylinder 37, said riveting die being held in position by means of the clip or clamp 41 of the usual construction. I have shown the handle 42 as omitted from Figs. 5 to 8 inclusive, although it will of course be understood that a handle is to be employed in conjunction with all of these tools when the same are used for metal work.

In the construction seen in Figs. 7 and 8, I have shown another embodiment of the principle of my invention as applied to a short stroke chipping or calking hammer wherein the piston 43 having a groove 44 is employed, said groove connecting the smaller head 45 of the piston to the body of the latter. I have shown precisely the same type and arrangement of valves, ports and passages as appears in Figs. 2 to 5 already described and I have consequently lettered the corresponding parts with corresponding reference figures and inasmuch as the same cycle of operation and the same coating ports and passages are employed throughout the tool seen in Figs. 7 and 8 as is employed in the tool seen in Figs. 1, 2, 3, 5 and 6, I have deemed it unnecessary to describe Figs. 7 and 8 in detail or to illustrate the same by a view similar to Figs. 1 or 6, since the corresponding parts will all appear substantially the same.

So far as I am aware, I am the first in the art to devise a valve mechanism which can be used interchangeably with cylinders of varying lengths as will be apparent from Figs. 1 to 3 and 5 to 8 and my claims to these features are therefore to be interpreted with corresponding scope.

While I have shown the tool cylinder and valve box and valve as being assembled by merely screwing the handle and sleeve 46 in position upon the tool cylinder, it will be evident that various other means of securing the handle, tool cylinder, valve box and valve in assembled position may be employed without departing from the spirit of my invention.

I desire to lay special emphasis upon the cheapness with which my valve mechanism can be produced, since there is no cap or cover required for the rear end of the valve box as is usually customary and since I make

the inner wall of the handle serve as the cover for the valve box said inner wall thus forms a stop for the rearward movement of the valve and also serves to contain the port 14 through which live motive fluid is constantly acting. Furthermore, it will be apparent that when the valve is in one position it will be held in that position positively and firmly and cannot be moved or shaken, since there is absolute exhaust on one end of the valve and absolute pressure on the other end as long as the proper ports are covered and vice versa when they are opened.

It will be evident that in my invention I accomplish the same result with a valve having equal pressure areas that has heretofore only been possible where a valve having differential pressure areas was employed; also that the latter construction is considerably more expensive and complicated and less durable than that employed in my invention.

It will be apparent that a plurality of ports and passages corresponding to the ones shown may be employed and that the length and diameter of these ports may be proportioned by the constructor to suit the requirements of the occasion and I do not, therefore, desire to be limited in every instance to the exact construction I have herein shown and described.

Having thus described my invention, what I claim as new and desire to secure by Letters Patent, is:—

1. In a pneumatic tool, a balanced valve, composed of two outer ungrooved heads and a central head all of uniform diameter, necks joining said heads, a valve box, having a rearwardly extending valve chamber, means for directing constant pressure upon said outer heads of said valve, and means for creating an exhaust passage intermittently at each end of said valve, said valve and valve box being in alinement with their piston.

2. In a pneumatic tool, a cylinder, a piston therein, a valve chamber open at its rear end, a valve in said chamber in alinement with said piston and, having a plurality of ungrooved heads of uniform diameter joined by necks, an inlet groove in said valve chamber controlled by said valve, ports and passages controlled by said valve for leading the motive fluid toward and away from the ends of said piston, ports leading into the front and rear portions of said valve chamber for admitting live motive fluid constantly to the ends of said valve, and passages controlled by the piston for permitting intermittent exhaust from the ends of said valve.

3. In a pneumatic tool, a cylinder, a piston therein, a valve box, a valve chamber open at its rear end, a valve in said chamber, having a central head and two outer ungrooved heads of uniform diameter joined by necks, an inlet groove in said box, controlled by

said central head, ports and passages controlled by said heads, for leading the motive fluid toward and away from the ends of said piston, ports leading into the front and rear portions of said valve chamber for admitting live motive fluid constantly to the outer ends of said valve and passages controlled by the piston for permitting intermittent exhaust from the ends of said valve.

4. In a pneumatic tool, a cylinder, a coverless valve box made in one piece, a balanced valve therein in alinement with said cylinder and having equal pressure areas formed of solid heads of the same diameter, means for directing constant pressure upon the outer area of each of said heads, and a handle secured to said cylinder and having its inner wall contacting with the rear wall of said valve box so as to form the rear closure for said valve box.

5. In a pneumatic tool, a cylinder, a coverless valve box made in one piece, a balanced valve therein having constant pressure on its ends, and a handle secured to said cylinder and having its inner wall contacting with the rear wall of said valve box so as to form the rear closure for said valve box, in combination with means for creating an exhaust passage intermittently at each end of said valve.

6. In a pneumatic tool, a cylinder, a valve chamber, a balanced valve in alinement with said cylinder and having heads of equal diameter adapted to be inserted in said chamber either end foremost, a handle secured to said cylinder, and having its inner wall forming a closure for said valve chamber, a main pressure supply duct leading through said handle to said valve box, a port leading from said supply duct to the rear end of said valve chamber, for conducting live motive fluid constantly thereto, and a second port leading through said valve box, for conducting live motive fluid constantly to the front end of said valve.

7. In a pneumatic tool, a cylinder, a valve box having a valve chamber open at its rear end, a balanced valve in alinement with said cylinder and having heads of equal diameter adapted to be inserted in said chamber either end foremost, a grasping handle secured to said cylinder, and having its inner wall forming a closure for said valve chamber, a main pressure supply duct leading through said handle to said valve box, a port leading from said supply duct to the rear end of said valve chamber, for conducting live motive fluid constantly thereto, and a second port leading through said valve box, for conducting live motive fluid constantly to the front end of said valve.

8. In a pneumatic tool, a valve for controlling ports common thereto and to a piston and consisting of a solid body having ungrooved outer and intermediate heads joined by necks, the outer ends of said valve being always exposed to live fluid pressure and in-

termittently to the exhaust and said valve being located exteriorly to said piston in alinement therewith and adapted to move in the same direction as said piston.

- 5 9. In a pneumatic tool, a solid piston, a valve adapted to move in the same direction as the latter, said valve consisting of a body provided with the outer and intermediate heads joined by necks, said outer heads being 10 ungrooved and always exposed to live fluid pressure and said central head being alternately exposed on either side to a greater volume of live fluid pressure, said heads being of the same diameter and said valve being 15 located out of the path of said piston, the movement of the latter terminating exterior to said valve and the latter being provided with exhaust passages which are open intermittently at each end of said valve.
- 20 10. In a pneumatic tool, the combination of a cylinder; a piston, ports and passages for conducting the motive fluid to and from said piston, a one piece valve box secured to an end of said cylinder and a solid balanced 25 valve having heads of uniform diameter in said valve box, the outer ends of said valve being ungrooved and always exposed to live fluid pressure and intermittently to the exhaust, said valve being located out of the 30 path of said piston and moving in the same direction as said piston when the latter is in the act of striking a blow upon the working tool.

- 35 11. In a pneumatic tool, a valve consisting of a solid body having two ungrooved outer and intermediate heads, necks joining said heads, the area of said outer heads being the same and having live motive fluid constantly acting thereupon, said heads being open intermittently to the exhaust and said valve being out of the path of the piston in alinement therewith and moving in the same direction as said piston.

- 40 12. In a pneumatic tool, the combination of a cylinder containing a piston, a one piece valve box located out of the path of the piston, an unapertured valve in said valve box, the movement of said piston being in line with said valve and terminating exterior to 45 said valve which latter is provided with opposing pressure areas against which live motive fluid constantly acts, said opposing pressure areas being of the same diameter and intermittently open to exhaust and said 50 valve moving in the same direction as said piston.

- 55 13. In a pneumatic tool, a cylinder, a piston therein, a one piece valve box, an unapertured valve therein moving in the same di-

rection as said piston in line therewith and 60 located at the rear and out of the path thereof, the movement of said piston terminating exterior to said valve, a handle engaging said cylinder and forming the assembling means for said valve box and cylinder, a valve, a 65 pressure supply duct of comparatively large area leading to said valve chamber and live air passages of a reduced area leading from the pressure supply duct of said handle to the ends of said valve chamber.

- 70 14. In a pneumatic tool, a cylinder, a one piece valve box located at an end thereof, a handle having thereon means engaging said cylinder for holding the latter, and said valve box in assembled position, a valve in said 75 valve box, a pressure supply duct leading from said handle into said valve box, a groove in the latter for leading motive fluid to opposite portions of said valve, live air passages 14, 11 and 12 for leading a restricted 80 supply of live motive fluid into each end of said valve box, the port 25, passage 26, port 24, port 27, passages 28 and port 29 for permitting exhaust of motive fluid from the forward end of said valve, a port 32, passage 33, 85 port 31 and port 30 for permitting exhaust of the motive fluid from the rear end of said valve, said ports 30 and 27 being controlled, by the piston as it nears the extreme limit of its stroke, in each direction, passages 7 and 8 90 in said valve box for permitting the entrance of motive fluid to drive the piston forwardly, said passages serving as exhaust passages as the piston moves in a rearward direction, 95 passages 19, 18 and 17 for permitting the inlet of the motive fluid to drive the piston rearwardly and a passage 21 serving in conjunction with said passages 19, 18 and 17 to permit exhaust from the forward end of said piston when the latter moves in a forward 100 direction.

15. In a pneumatic tool, a cylinder, a piston therein, a valve box, a solid balanced valve therein having three heads of uniform diameter, said valve moving in substantial 105 alinement with said piston, means for directing constant pressure upon each outer head of said valve, and means for creating exhaust intermittently at each end of said valve, whereby the same valve and valve box can be used interchangeably with a solid or ungrooved piston, or with a long stroke or short stroke cylinder.
